CROSSWALK SIGN

Robert E. McCormick and Ronald B. Kuchenreuther, Bellevue, and John L. Miller, Kirkland, Wash., assignors to Van Tone Millworks, Inc., Seattle, Wash., a corporation of Washington

Filed Dec. 26, 1967, Ser. No. 9,924

Term of patent 14 years

(Cl. D72—1)

The figure is an isometric view of a crosswalk sign embodying our new design, the opposite side being substantially the same in appearance as the side shown.

We claim:

The ornamental design for a crosswalk sign, as shown and described.
